Inventor
By his Attorney
John E. Earle

United States Patent Office.

J. J. MARCY, OF MERIDEN, CONNECTICUT, ASSIGNOR TO HIMSELF AND
E. MILLER & CO., OF SAME PLACE.

Letters Patent No. 98,986, dated January 18, 1870.

IMPROVEMENT IN OIL-CAN VENT-SPOUTS.

The Schedule referred to in these Letters Patent and making part of the same.

To all whom it may concern:

Be it known that I, J. J. MARCY, of Meriden, in the county of New Haven, and State of Connecticut, have invented a new Improvement in Vent-Spout for Oil-Cans; and I do hereby declare the following, when taken in connection with the accompanying drawings, and the letters of reference marked thereon, to be a full, clear, and exact description of the same, and which said drawings constitute part of this specification, and represent, in—

Figure 1, a vertical central section, the vent open; and in

Figure 2, a vertical central section, the vent closed.

This invention relates to an improvement in the oil-can tube patented to E. B. Beach, July 7, 1868, of which patent the aforesaid E. Miller & Co. hold the exclusive right, the object of the invention being to vent the can so that the pouring may be performed without difficulty; and consists in arranging in the tube, upon a single stem, two valves, the one a little distance above the other, and combined with an air-tube, leading from the valve-tube above the spout into the can, so that when the two valves are raised, both the spout and air-tube are open, and when the valves are depressed, both are closed.

A is the can, of common construction;
B, the valve-tube;

C, the spout;

a, the valve, fixed to the valve-stem d, so that when the stem is raised, as in fig. 1, the spout is open, and when depressed, as in fig. 2, the spout is closed.

As thus far described, the construction is the same as in the Beach patent, before referred to, but it will be observed, that means are required for vent other than that afforded by the spout. For this purpose, I arrange a tube, D, opening into the can, and into the tube B, above the spout, and arrange upon the valve-stem a second valve, f, above the valve a, so that when the valves are raised to open the spout, the tube D is also opened into the tube B, and an opening, i, through the tube B, permits air to pass through the tube B into the can, at the same time oil is poured from the spout; and when the valves are forced down, as in fig. 2, both tubes are closed.

I claim, as my invention—

In combination with the tube B, spout C, and valve a, a second valve, f, and tube D, opening into the tube B and can A, the whole constructed and arranged so as to operate as herein set forth.

J. J. MARCY.
